CLOSURE FOR CONTAINERS

Joseph C. Hoffman, Yonkers, N. Y.

Application January 9, 1935, Serial No. 994

2 Claims. (Cl. 229—43)

The invention relates to closures for containers and has for its object to provide an efficient closure of novel construction capable of being easily combined with the container and readily removed therefrom at will. The invention further contemplates the provision of an auxiliary closure adapted to be readily placed in position on and removed from the container as an auxiliary to the normal cover for said container or as a substitute therefor after the efficiency of said cover to close the container has been partially or completely destroyed because of the initial removal of said cover from said container. Other more specific objects will appear from the description hereinafter and the features of novelty will be pointed out in the claims.

In the accompanying drawing, which illustrates several forms of the invention without defining the limits thereof, Fig. 1 is an elevation of a container partly in section with one form of the novel closure combined therewith; Fig. 2 is a plan view of Fig. 1 with parts in section; Fig. 3 is a view similar to Fig. 1 showing another form of the novel closure; Fig. 4 is a plan view of Fig. 3 with parts in section, and Fig. 5 is a fragmentary elevation of a container partly in section and illustrating still another form of the novel closure.

For descriptive and illustrative purposes the several forms of the novel closure are shown in connection with containers of the type in which a normal cover is frictionally secured in an annular fitting located at one end of said container. The efficiency of such covers as a closure is in many instances reduced and even destroyed subsequent to the initial removal of said covers, and the novel closures are in such cases designed to serve as auxiliaries to or substitutes for said normal covers after the initial removal thereof from the cooperating fitting. While the novel closures are specially adapted for use in connection with the indicated and illustrated type of containers, it is to be distinctly understood that said closures are not limited to such use and that they may be efficiently utilized in connection with other forms of containers.

In the drawing the containers 10 are of cylindrical form and in many instances are constructed of cardboard, paper board or equivalent material, said containers 10 each being permanently closed at one end with a bottom 11 fixed in place in any conventional and well-known way. At their opposite end the containers 10 of the indicated type are each provided with an annular metallic fitting 12 which is fixed

in place, for instance, by being crimped upon the container 10 in the customary manner. In the forms shown in Figs. 1, 2 and 5 the crimping of the annular fitting 12 is such that an outwardly extending shoulder illustrated in the form of an annular external shoulder 13 is formed upon the container 10, while in Figs. 3 and 4 the fitting 12 is crimped upon the container 10 so as to lie flush with the exterior surface thereof. In any case the annular fitting 12 is generally provided with a lip or flange 14 which extends in the direction of the axis of the container 10 and defines the opening at one end through which access to and egress from the interior of the container 10 may take place. The cover 15 which normally closes the open end of the container 10 may be of any customary type and initially is forced into the opening defined by the lip 14 so as to be frictionally held in place therein to efficiently seal the open end of the container 10. When it is desired to initially remove the cover 15 this may be done by prying the same from the opening defined by the lip 14, by means of a suitable implement such as a screw-driver or knife in co-operation with the transverse portion 15^a of said cover 15. After such initial removal the cover 15 in many cases is no longer of maximum efficiency as a closure and in some instances is incapable of being replaced in an effective closing position. Under such conditions the novel closure, as illustrated in the drawing, is designed to act as an auxiliary to or as a substitute for the cover 15 in closing the open end of the container 10.

In all of the forms shown in the illustrated examples the novel closure consists of a circular end portion 16 and a peripheral flange 17, the dimensions of the end portion 16 being such that the internal diameter of the flange 17 is somewhat greater than the external diameter of the container 10. In those forms which include the annular shoulder 13 or equivalent outwardly extending shoulder, the internal dimensions of the continuous flange 17 is such that said flange fits over said shoulder and projects beyond the same in an axial direction in spaced relation to the container 10 as shown in Figs. 1 and 5; in forms of the type shown in Fig. 3 the flange 17 throughout its axial width is in spaced relation to the container 10 when the closure is in position thereon.

In any case the flange 17 is provided with inwardly directed means whereby the closure is removably secured on the container 10, the means in question being of such type that it will permit

the closure to be readily removed from and placed upon the container 10, and at the same time firmly hold said closure in operative position thereon. In Figs. 1 and 2 the aforesaid means 5 is shown in the form of a plurality of inwardly directed projections 18 spaced apart circumferentially of the flange 17 and arranged to snap and extend beneath the shoulder 13 at spaced intervals and in co-operation therewith to removably secure the closure on the container 10. In Figs. 3 and 4 the inwardly directed means 10 consists of a plurality of inwardly directed projections 18^a which extend axially of the flange 17 at spaced intervals; when the closure is in position 15 in the container 10 the projections 18^a are in frictional engagement with the outer surface thereof and thereby serve to removably secure the closure in place on the container 10. In Fig. 5 a continuous inwardly directed projection 18^b 20 shown in the form of an annular inwardly directed projection or bead constitutes the inwardly directed means; this projection 18^b snaps and extends beneath the shoulder 13 and in co-operation therewith secures the closure in operative 25 position on the container 10.

It will be understood that the inherent elasticity of the flange 17 permits the projections 18 and 18^b to be forced over the shoulders 13 when the closure is placed upon the container 10, and causes said projections to snap beneath said shoulders 13 when said closure is in its operative position on said container 10. Similarly this elasticity of the flange 17 forces the projections 18^a into frictional engagement with the outer surface of the container 10 in Figs. 3 and 4 to hold the closure in place thereon.

As shown in the drawing the projections 18, 18^a and 18^b may be formed by deforming or indenting the flanges 17 inwardly, it being understood however that this is not an arbitrary requirement and that said projections may be otherwise formed if desired.

While the novel closure has been illustrated in connection with containers of cylindrical shape 45 and is itself illustrated in circular form, it will be

obvious that said closure in the proper form may be used with equal efficiency in combination with containers having a cross-sectional form other than circular. It will further be obvious that the novel closure is not restricted in its use to containers having closing means such as exemplified by the covers 15 although it is particularly adapted to this type of container for the reasons set forth hereinbefore. In addition it will be apparent that the novel closure is equally well adapted for use 10 in connection with containers made of materials other than cardboard, paper board or equivalent material.

The novel closure in all of its forms serves as a means for efficiently closing the open end of a 15 container when for instance only part of the contents thereof have been removed or for other reasons.

Various changes in the specific forms shown and described may be made within the scope of 20 the claims without departing from the spirit of the invention.

I claim:

1. The combination of a container of non-metallic material, a metallic fitting fixed upon 25 said container at one end and projecting over the outer surface thereof in an axial direction, a closure including a continuous flange adapted to project over said container in outwardly spaced relation thereto, and inwardly directed means on 30 said flange bridging the space between the latter and said container and adapted to removably secure said closure on said container.

2. The combination of a cylindrical non-metallic container including an open end, an annular metallic fitting fixed upon said open end and projecting over the outer surface thereof in an axial direction, an auxiliary closure provided with an annular flange adapted to project over said container in outwardly spaced relation thereto, and inwardly directed means on said flange bridging the space between the latter and said container and adapted to removably secure said auxiliary closure on said container.

JOSEPH C. HOFFMAN.
